UNITED STATES PATENT OFFICE.

ANDY FASENMAYER, OF TITUSVILLE, PENNSYLVANIA, ASSIGNOR OF ONE-HALF TO WILLIAM BAYLISS, OF TITUSVILLE, PENNSYLVANIA.

PIPE-WRENCH.

SPECIFICATION forming part of Letters Patent No. 736,372, dated August 18, 1903.

Application filed February 12, 1903. Serial No. 143,052. (No model.)

To all whom it may concern:

Be it known that I, ANDY FASENMAYER, of Titusville, Crawford county, Pennsylvania, have invented a new and useful Pipe-Wrench, of which the following is a full, clear, and exact description, reference being had to the accompanying drawings, forming part of this specification, in which—

Figure 1 is a side elevation of my improved wrench with the parts in position to engage a pipe. Fig. 2 is a similar view showing the parts gripped as the pipe is turned, and Fig. 3 is a plan view.

My invention relates to that class of pipe-wrenches wherein the swinging jaw is pivoted to the handle and the pinching-jaw is pivoted to the outer end of the first jaw and has a recess engaging a prong at the end of the handle. This is a well-known and popular type of pipe-wrench which is largely used, especially in oil-well works. Heretofore in using such a wrench as the wrench is turned to get a new hold upon the pipe, especially in working on a ground-pipe, the jaws often drop apart, and in using this type of wrench it is common for the operator to hold the jaws together with his hand when reaching for a new grip on the pipe. My invention overcomes this difficulty and provides a lock which holds the jaws from dropping apart and allows sufficient motion to grip and release the pipe in the opposite movements of the wrench-lever.

It also consists in providing means for holding the locking device both in open and closed position.

In the drawings, 2 represents the wrench-handle, having at its front end a prong 3. To this front end is pivoted the wrench-jaw 4, which is preferably in the form of a casting having side ears 5, forming a curved recess therein. This casting is preferably provided with ears or lugs 6, which embrace the handle and are pivoted on pin 7.

To the outer end of the jaw-casting 4 is pivoted the gripping-jaw 8, in which the steel gripping-piece 9 is fastened in the usual manner. In the end of this gripping-jaw 8 is a recess 10, which is arranged to engage the prong 3 on the handle when the wrench is placed upon the pipe to turn it.

The above-described parts are old and well known, and I make no claim thereto.

To prevent the gripping-jaw from falling away during the turning, I provide a locking device, which in the form shown consists of a dog 11, having ears 12, which straddle the handle and are pivoted on the screw-bolt 13, extending through the handle. The end of this dog is arranged to engage a transverse recess 14 in the back of the jaw 4, allowing enough freedom of movement to tighten and loosen the wrench, as shown in the two positions of Figs. 1 and 2; but the jaws cannot become disengaged, since the backward swing of the jaw 4 to a point sufficient to disengage the jaw 8 from the prong 3 is stopped by the dog. To hold the dog in closed position, I preferably employ a curved spring 15, having a prong 16 at one end entering a hole in the handle, and an oppositely-projecting prong 17 entering a hole in the hub or ear of the dog. The dog is cut away on this side, as shown in dotted lines, to admit the bent spring. The spring serves not only to hold the dog in closed position, but also to retain it in open retracted position, and in Fig. 2 I show such open position in dotted lines. In this case the prong 17 of the spring passes the line between the screw-bolt 12 and the prong 16, and thereby retains the dog in open position.

In using the tool the gripping-jaw is swung back, the wrench is placed around the pipe, and the jaw 8 then swung in so that the prong 3 engages its recess. The locking-dog is then swung forward into position, and the wrench may be operated without possibility of its dropping away from the pipe.

The advantages of my invention result from the use of the lock, which holds the jaws around the pipe and prevents the dropping off of the wrench. The operator may use the device with one hand, leaving the other hand free.

The attachment is simple and may be easily and cheaply made and attached.

I claim—

1. A pipe-wrench having a jaw pivoted to the handle, said jaw having an abutment in its outer face beyond the pivot-recess, another

jaw pivoted to the outer end of the first jaw and having loose engagement with the handle, and a pivoted locking device arranged to engage the abutment on the first jaw; substantially as described.

5 2. A pipe-wrench having a jaw pivoted to the handle and provided with a recess in its outer face beyond the pivot-recess, another jaw pivoted to the outer end of the first jaw 10 and having lug-and-recess engagement with the handle, and a pivoted locking device on the handle arranged to engage the intermediate recess in the first jaw; substantially as described.

15 3. A pipe-wrench having a jaw pivoted to the handle, another jaw pivoted to the outer end of the first jaw, and having a loose en-

gagement with the end of the handle, a locking device engaging the first jaw, and a spring arranged to retain the lock in operative position; substantially as described.

4. A wrench having a jaw pivoted to the handle, another jaw pivoted to the first jaw and engaging the end of the handle, a locking-dog engaging the first jaw, and a spring arranged to hold the dog in both open and closed positions; substantially as described.

In testimony whereof I have hereunto set my hand.

ANDY FASENMAYER.
